HUDSON MAXIM, OF BROOKLYN, NEW YORK, ASSIGNOR TO THE E. I.
DU PONT DE NEMOURS POWDER COMPANY, OF WILMINGTON,
DELAWARE, A CORPORATION OF NEW JERSEY.

EROSION-METER.

No. 829,117.

Specification of Letters Patent.

Patented Aug. 21, 1906.

Application filed May 24, 1904. Serial No. 209,548.

To all whom it may concern:

Be it known that I, HUDSON MAXIM, a citizen of the United States, residing at Brooklyn, city of New York and State of New York, have invented a new and useful Improvement 5 in Erosion-Meters, of which the following is a full, clear, and exact description, reference being had to the accompanying drawings, which form a part of this specification.

The present invention relates to improvements in erosion-meters—that is to say, in apparatus or devices for testing or determining the relative erosive character of the products of combustion of gunpowder charges 15 when fired in guns.

The object of the invention is mainly to determine the relative effects which the products of combustion of gunpowder charges will have to erode or cut away the bore of the 20 gun from windage or passage of the gases by the projectile in its flight through the bore of the gun and also the eroding effect upon the powder-chamber of the gun due to the direct impingement of the gases upon the walls of 25 the same.

I accomplish this object by providing a removable eroding-surface which I place in the powder-chamber of the gun, so that in firing the gun the gases impinge thereon and the 30 extent of the erosion produced may be readily measured. This erosion-surface may be the walls of an orifice or the gases may impinge directly against a surface.

I preferably carry out my invention as follows: A strong hollow steel cylinder is provided of sufficient strength to withstand the maximum chamber-pressure in the gun, said hollow cylinder having a removable disk with a small central perforation through which the 35 gases enter the interior of the cylinder and held securely in place closing the mouth of the cylinder. The disk is preferably held in place by a screw-cap with a gasket, preferably of copper, interposed between the disk and the end or peripheral edge of the cylinder, so that the unbalanced pressure on the exterior of the disk will hold it firmly in place upon the gasket, forming a gas-tight joint between the disk and the peripheral edge of the 40 cylinder. The hollow closed cylinder having the small erosion-perforation is adapted to occupy a more or less small portion of the powder-chamber of the gun. When the gun

is fired, the heated gases rushing into the cylinder through the small perforation will erode 55 or cut away the walls of said perforation, and by caliper or measuring this opening after firing the gun its enlargement or the amount of erosive action of the gases is determined.

When firing a gunpowder charge consisting of pure nitrocellulose smokeless powder, there is much less erosive action than when firing a charge of cordite or smokeless powder rich in or containing a large percentage of nitroglycerin or other oxidizing agent or ingredient capable of evolving great heat during combustion. Furthermore, when a sufficient charge is used of a given powder to produce a very high chamber-pressure—say from forty thousand or forty-five thousand to 60 fifty thousand pounds to the square inch—there is greater erosive action than when a chamber-pressure of from thirty thousand to thirty-five thousand pounds to the square inch is employed. The present invention 65 therefore serves both to determine the relative erosive qualities of the gases of different powders under like pressures and of the same gunpowder burned under different pressures.

In addition to and as a substitute for the 70 central perforation of the disk I may and sometimes provide an impact-surface against which the gases passing through the perforation are allowed to impinge, and by the character and size of the pit formed in the exposed 75 impact-surface the relative erosive character of the gases is also determined in addition to the means already described.

In the accompanying drawings, Figures 1 to 4, inclusive, are longitudinal sections illustrating different forms of the improvement.

The erosion-testing device consists, essentially, of a strong hollow closed steel cylinder 10, having through one of its walls a relatively small perforation 9 for the passage of 90 the gases to the interior of the cylinder. In the preferred construction of the testing device the erosion-perforation 9 is provided in a removable disk 11 and located centrally 95 therein, closing one end of the cylinder. As a means for confining the disk in place an open screw-threaded cap 12 is provided 100 screwed onto the end of the cylinder, and to make the joint between the disk and the peripheral end of the cylinder gas-tight there is 105 interposed a gasket 8, preferably of copper.

Because of the necessary thickness of the disk and to make the erosion-perforation as short as is desirable the front or back of the disk has a wide countersunk opening 7 communicating with the perforation.

In Fig. 2 the hollow cylinder supports a centrally-arranged rod 14, passing through a relatively large central perforation 19 in the disk, so as to form with the end of the rod a narrow annular opening for the passage of the gases to the interior of the cylinder. In addition to the annular opening the wall of the rod 14 may have one or more longitudinal grooves 6, forming other erosion-surfaces which may be calipered to determine the erosive character of the gases.

In Figs. 3 and 4 the testing device is provided with an impact-surface 5, directly opposite and in front of the small perforation 9 to receive the impact of the gases rushing through said perforation, so as to become pitted thereby and serve as a means of determining the character of the gases. In Fig. 3 the impact-surface is provided by a thin metallic disk 4, removably seated in the face of the impact-surface, the latter being formed by an open disk or spider 15, confined in place against the gasket by a spacing-ring 16 of proper height between the centrally-perforated disk and the impact-spider. In Fig. 4 the impact-surface is provided by a spider 17, screw-threaded onto the end of a central supporting-rod 18.

The improvements, it will be understood, are capable of partaking different forms, and hence are not necessarily limited to those shown.

Having now fully described my invention, what I claim, and desire to protect by Letters Patent, is—

1. An erosion-meter for guns, comprising a removable metallic piece, adapted to be placed within the powder-chamber and against one surface of which the gases in firing impinge.
2. An erosion-meter for guns comprising a removable orificed plate adapted to be placed within the powder-chamber the orifice being in the path of the gases in firing.
3. An erosion-meter for guns comprising a removable metallic piece and an orificed plate, the orifice and one surface of the metallic piece being in the path of the gases in firing.
4. An erosion-meter for guns comprising a chamber, one wall of which is provided with a perforation and adapted through said perforation for communication with the powder-chamber of a gun.
5. An erosion-meter for guns comprising a chamber, one wall of which is removable and provided with a perforation and adapted

through said perforation for communication with the powder-chamber of a gun.

6. An erosion-meter for guns comprising a strong hollow closed cylinder, having a small perforation through one of its walls and adapted to occupy a place in the powder-chamber of a gun.

7. An erosion-meter for guns comprising a strong hollow closed cylinder, having a small perforation through one of its walls and adapted to occupy a place in the powder-chamber of a gun, said perforated wall being removable.

8. An erosion-meter for guns comprising a strong hollow closed cylinder, having a removable centrally-perforated disk forming one of the walls of the cylinder, and adapted to occupy a place in the powder-chamber of a gun.

9. An erosion-meter for guns comprising a strong hollow closed cylinder, having a removable centrally-perforated disk forming one wall of the cylinder, and secured in place by a screw-cap, and adapted to occupy a place in the powder-chamber of a gun.

10. An erosion-meter for guns comprising a strong hollow closed cylinder having a small perforation through one of its walls and an impact-surface supported within the cylinder opposite the perforation, and adapted to occupy a place in the powder-chamber of a gun.

11. An erosion-meter for guns comprising a strong hollow closed cylinder having a small perforation through one of the walls and a removable impact-surface supported within the cylinder opposite the perforation, and adapted to occupy a place in the powder-chamber of a gun.

12. An erosion-meter for guns, comprising a metallic piece adapted to be placed in communication with the powder-chamber and against one surface of which the gases in firing impinge.

13. An erosion-meter for guns comprising an orificed plate adapted to be placed in communication with the powder-chamber and through which the gases in firing pass.

14. An erosion-meter for guns, comprising a metallic piece and orificed plate adapted to be placed in communication with the powder-chamber, the orifice and one surface of the metallic piece being in the path of the gases in firing.

In testimony of which invention I have hereunto set my hand, at Dover, New Jersey, on this 19th day of May, 1904.

HUDSON MAXIM.
